No. 610,946.

Patented Sept. 20, 1898.

W. F. NIEBLING.
WATER COOLING DEVICE.

(Application filed Dec. 23, 1897.)

(No Model.)

UNITED STATES PATENT OFFICE.

WILLIAM F. NIEBLING, OF CINCINNATI, OHIO.

WATER-COOLING DEVICE.

SPECIFICATION forming part of Letters Patent No. 610,946, dated September 20, 1898.

Application filed December 23, 1897. Serial No. 663,132. (No model.)

To all whom it may concern:

Be it known that I, WILLIAM F. NIEBLING, a citizen of the United States, and a resident of Cincinnati, Hamilton county, State of Ohio, have invented a certain new and useful Water-Cooling Device; and I do declare the following to be a clear, full, and exact description of the invention, such as will enable others skilled in the art to which it appertains to make and use the same, attention being called to the accompanying drawings, with the reference-numerals marked thereon, which form a part of this specification.

This invention relates to means for cooling water when the latter, after having been used in a certain manner and for certain purposes, has become hot or warm and when it is necessary to cool the same to permit it to be used again. Such a condition arises, for instance, in refrigerating plants, where water is used to cool the condensers and where it is an object to reuse this water, which otherwise would go to waste.

The cooling contemplated by my invention extends only as far as it is possible to be attained by using the then-prevailing temperature of the atmosphere, and while at times such cooling may be insufficient, requiring additional cooling by artificial means, it is nevertheless to the extent attained a clear gain at all times, reducing the cost of such artificial cooling, since the use of my device requires no operating expenses.

In the following specification, and particularly pointed out in the claims, is found a full description of the invention, its operation, parts, and construction, which latter is also illustrated in the accompanying drawings, in which—

Figure 1 is a vertical elevation, partly in section, of my device. Fig. 2 is a top view of one of the receiving-pans. Fig. 3 is a reduced side elevation of the water-motor. Fig. 4 is a sectional detail view of the top bearing of the upright shaft. Fig. 5 is a diagrammatic top view, at reduced scale, of the device.

The water to be cooled is discharged from a pipe 8 and received by the upper one of a series or stack of pans 9, preferably of circular shape and with perforated bottoms, so that the water falls successively from one pan to the other. Downwardly—that is, from one

pan to another—these perforations decrease in size, but increase in number, so that the discharging streams of water decrease correspondingly in size and increase in number. The exposure of the water to the cooler atmosphere by the increasing number of thin streams or jets passing through the air is thereby also extended and the desired result more readily obtained. The increasing number of smaller holes requires a progressive enlargement downwardly of the size of the pans to prevent overflowing. They are supported one above the other and with a space between them in any suitable manner—as, for instance, by brackets 11, projecting from an upright post 12. The exposure of the water to the air, both as to time and space, is increased while flowing from one pan into the other by causing these latter to rotate, for which purpose upright 12 assumes also the function of a rotary shaft supported in suitable bearings at both its ends. At the lower end I provide for such purpose a flange 13, fitted into a box 14, with antifriction-balls 15 between them. At the upper end I use a recessed journal 16, rotating in a bearing 17, with antifriction-rollers 18 between the two. A nut 19 closes the space occupied by these rollers. Bearing 17 is sustained by suitable stays, braces, or, as shown, by so-called "hog-chains" 21, which connect to posts 22. Supporting-shaft 12 may be rotated by any means, but I prefer such requiring no operating expenses, and which I attain by providing a water-motor driven by the water discharged from the lowermost pan. For such purpose this water is collected and concentrated in a tank 23, from which, through a pipe 24, it discharges upon the wheel 25 of a suitable water-motor, as shown in Fig. 3.

Shaft 12 passes loosely through tank 23, the bottom of which is cut out thereat. To prevent leakage at this point, a sleeve or wall surrounding shaft 12 is carried up from this opening in the bottom of the tank. (See dotted lines in Fig. 1.) The resulting rotation of wheel 25 is received by a shaft 26, supported in bearing 27, and transmitted to shaft 12 by a set of bevel-gears 28. By having two of these latter mounted on a sleeve 29, lengthwise movable on shaft 26, but for rotation connected thereto by the customary sliding key or spline on one fitting and moving in a

groove in the other, the direction of rotation of shaft 12 may be reversed. Such reversal is especially desirable where I also take advantage of the wind in this manner that 5 the device is caused to rotate against the same, as shown in the diagram in Fig. 5. Since the action of the wind in this manner is available only for half of the device, its other half must be closed, which is best done 10 by an angular partition 31, which should be movable to be adjustable to the veering of the wind. The cooled water discharged from pipe 24 after its action upon the water-motor is received by a tank 32, from which it discharges 15 through an outlet 33 to be conveyed to the place of its reuse. It may go direct to such place, or, if necessary, be subjected first to additional cooling by artificial means.

34 is an additional bearing at the extreme 20 lower end of shaft 12. Where the quantity of the water discharged from pipe 8 is not constant and decreases sometimes, so as not to completely spread over the discharging area of the pans, such area is reduced—that is, part 25 of the openings therein are closed by flaps 35, a sufficient number of which may be provided. When up, as shown, the full discharge is obtained; but when down such discharge is reduced to the extent of the openings covered 30 by said flaps.

Having described my invention, I claim as new—

1. In a device for cooling water, the combination of a number of pans having perforated bottoms, a water-pipe discharging into the uppermost pan, a central upright shaft on which they are supported, one below the other with a space between them and means to rotate 35 said shaft.

40 2. In a device for cooling water, the combination of a number of pans with perforated bottoms, a water-pipe discharging into the uppermost pan, a central upright shaft on which they are supported, one below the other with 45 a space between them, the size of such pans increasing and the perforations therein decreasing successively downwardly and means to rotate the upright shaft.

3. In a device for cooling water, the combination of a number of pans with perforated bottoms, a water-pipe discharging into the uppermost pan, a central upright shaft on which they are supported, one below the other with a space between them, a water-motor for rotating said shaft and means for directing the water discharged from the lowermost pan to actuate such motor.

4. In a device for cooling water, the combination of a number of pans with perforated bottoms supported one above the other with a space between them to permit access and passage of air, a water-pipe discharging into the uppermost pan and an angular partition 31, adjustably supported and adapted to surround a part of the stack of pans thereby restricting access of air to them only from the side left open by the partition.

5. In a device for cooling water, the combination of a number of pans with perforated bottoms, a water-pipe discharging into the uppermost pan, a central upright shaft capable of rotation and on which they are supported, one below the other with a space between them and an angular partition 31 adjustably supported and adapted to shield and inclose one-half of the stack of pans. 70

6. In a device for cooling water, the combination of a number of pans with perforated bottoms supported one above the other with a space between them, a water-pipe discharging 80 into the uppermost pan and adjustable flaps adapted for closing a number of the openings in the perforated bottoms.

7. In a device for cooling water, the combination of a number of pans having perforated bottoms, a water-pipe discharging into the uppermost pan, a central upright shaft on which they are supported, one below the other with a space between, means to rotate said shaft, a journal 16 at the upper end of the latter, a bearing 17 within which it rotates, antifriction devices between the two and means to sustain bearing 17 in a central position. 85

8. In a device for cooling water, the combination of a number of pans having perforated bottoms, a water-pipe discharging into the uppermost pan, a central upright shaft on which they are supported, one below the other with a space between, means to rotate said shaft, a flange 13 near the lower end of the latter, a 100 box 14 which receives it and antifriction devices between the two.

9. In a device for cooling water, the combination of a number of pans having perforated bottoms, a water-pipe discharging into the uppermost pan, a central upright shaft on which they are supported, one below the other with a space between them, a tank which receives the water from the lowermost pan, a water-motor which receives the concentrated discharge from said tank and is driven thereby 110 and operative connection whereby said water-motor is enabled to rotate the upright shaft. 105

10. In a device for cooling water, the combination of a number of pans having perforated bottoms, a water-pipe discharging into the uppermost pan, a central upright shaft on which they are supported, one below the other with a space between them, a tank 23 which receives the water from the lowermost 120 pan, a water-wheel 25 mounted upon a horizontal shaft 26, a pipe which guides the concentrated discharge from tank 23 upon said water-wheel, operative connection between shaft 26 and the upright pan-supporting shaft 125 whereby the latter is rotated and a tank 32 which receives the cooled water after it has left the water-wheel.

In testimony whereof I hereunto affix my signature in presence of two witnesses.

WILLIAM F. NIEBLING.
